PROCESS AND DEVICE FOR OZONIZING TOBACCO

Filed July 9, 1928

Inventor:

Samuel Rosenhoch.

UNITED STATES PATENT OFFICE

SAMUEL ROSENHOCH, OF BREMEN, GERMANY

PROCESS AND DEVICE FOR OZONIZING TOBACCO

Application filed July 9, 1928, Serial No. 291,283, and in Germany July 11, 1927.

This invention relates to a process of and device for refining raw tobacco by treatment with ozone.

Ozone treatment of tobacco for the purpose of an easy and complete destruction of microbes, is well-known. It applies particularly to microbes contained in water, the ozone being employed in very small quantities. However, a practical process whereby the tobacco leaves may be prepared for the reception of the ozone has not so far been made known.

The object of the invention is to refine the raw tobacco in such a manner that all its good qualities will be utilized to the full extent while less good and bad qualities are suppressed.

The quality of tobacco is, as is well-known, dependent on its origin, its treatment, fermentation, manipulation and storing as well as on the weather, the climate, kind of manure employed in the growth of the tobacco and on other circumstances. Raw tobacco of all kinds and origins, even if of the best quality, can under given conditions and treatment, be affected with diseases which the most experienced experts are unable to detect. A good many tobaccos do not reveal any change in structure and colour and are yet laden with microbes which set up, in the half-finished or finished product, putridities which are harmful to the human organism. At all events, the diseases of tobacco, whether the latter is in the raw or in the finished state, are almost always due to the activity of microorganisms. Besides, the raw substance can, through various causes such as soil and weather conditions, be subjected to a qualitative change without any accompanying change in the colour. Such changes are therefore difficult to recognize during the treatment, and diseased tobacco is therefore liable to be treated and stored in such a manner that putridity is bound to set in.

The present invention is based on a complete recognition of the nature and composition of the raw tobacco which mostly contains combustible and volatile substances such as

1. Acids, for instance nitric and organic acids,
2. Bases, for instance ammonia, nicotine and allied alkaloids, and
3. Indifferent substances such as cellulose, lignine, starch, albumen, wax, pectin, nicotine, and others.

It is true that long ago it has been proposed to improve tobacco and to prepare it for fermentation by bringing it into contact with ozone either in gaseous form or dissolved in a liquid and mixed with ammonia. This process failed, however, in that the ammonia tended on the one hand to decompose the tobacco and on the other hand to preserve the tobacco in its raw state. But even if the ammonia were left out, the treatment of the tobacco with ozone for the purpose of fermentation, as has previously been done, tends to increase the microbes instead of annihilating them, and the fermentation itself with ozone has not been successful owing to the difficulty of ensuring a uniform treatment.

In order to free the raw tobacco from microbes and refine it in such a manner that the necessary and valuable qualities are retained while neutralizing the acids and bases, which detrimentally affect the valuable substances during the burning of the tobacco, the following process has been devised:

The raw tobacco is in the first place cleared at the rib ends of all foreign matter such as insects, larvæ, eggs and the like. This may be effected by means of a brush. The rib ends are then slightly moistened with sterilized water at room temperature, several hours being allowed for the moisture to penetrate into the leaves. The latter are next separated, foreign plant matter and impurities are removed, and the leaves, the diseased as well as the healthy ones are now moistened in their entirety with sterilized water and kept in moist condition for 10 to 16 hours whereupon the leaves are taken by means of a suitable conveying and mixing device through a current of ozone which is so proportioned that the quantity of ozone is in strict accordance with the quantity of nicotine contained in the raw tobacco. Thus,

tobacco containing a large quantity of nicotine is moved slowly through a speedy current of ozone while the opposite conditions prevail in the case of tobacco containing little nicotine.

- 5 The gaseous ozone does not readily penetrate into the tobacco leaf owing to the resinous nature of the cuticle which on the other hand is essential for the proper glowing of 10 the tobacco and for the production of the aroma. The invention includes a process of and device for treating the tobacco electrically so as to break up the cell structure and enable the ozone to penetrate into the leaf. 15 This is effected by spreading the tobacco thinly over an electrically charged conveying device consisting of rollers, bands or the like whereby it is taken through the ozone current.
- 20 Tobacco is built up of three kinds of cells, the mesophyl forming the inner and larger part of the leaf, the stringy structure forming the nerve, and the epidermis which covers the inner part of the leaf. The electric treatment breaks up the different cells, without any destruction of aromatic resins or oils, so that the ozone can enter the leaf and effect its refinement.

In the accompanying drawings several 25 forms of devices for carrying out the invention are shown diagrammatically,

Fig. 1 representing a longitudinal section of the ozonizing machine,

Fig. 2, a part view of the conveying band, 30 Fig. 3, a top view of the band, and

Figs. 4 and 5 are views of modifications.

According to the invention the tobacco is first brushed so as to clear away foreign matter such as insects, larvæ, dust and the like. 35 Then it is slightly moistened with sterilized water, i. e., water which has been freed from microbes and lime, and left for about 5 to 10 hours so as to allow the moisture to be equally distributed. The tobacco leaves are next separated, foreign plant matter is removed, and 40 the leaves, the diseased as well as the healthy ones, are again moistened with sterilized water at room temperature and left in moist state for about 10 to 16 hours whereupon they are taken by a suitable conveying device 45 through a current of ozone. The conveying device is adapted to expose all parts of the leaf uniformly to the action of the ozone which should be proportioned in accordance 50 with the nicotine contents of the tobacco.

The following is an example of the process carried out with 100 kgs. tobacco composed of a mixture of three kinds of different nicotine contents, for instance

- 55 30 kgs. Montenegrine tobacco
40 kgs. Bulgarian tobacco, and
30 kgs. Salonican tobacco.

Each tobacco bundle is first brushed at the rib end with a root brush so as to remove as far as possible all the foreign substances, and

the rib ends are thereupon slightly moistened, preferably by means of a spray. The bundles are left for about 5 hours for the moisture to penetrate whereupon they are loosened and, while diseased leaves are retained, all foreign plant matter and impurities are removed. The three kinds of tobacco are then mixed in the above proportions, the mixed product is now moistened in its entirety with sterilized water, the moisture being allowed about 70 twelve hours to penetrate into the tobacco. Then the leaves are placed on a conveying and mixing device. The conveying elements consist preferably of endless hemp bands and they are used for taking the leaves through an ozone current in opposite direction to the latter. The ozone is proportioned as follows:

The percentage of nicotine in the above-mentioned tobacco mixture is about 6.2 per cent. For 100 kgs. of the mixture 0.125 grammes ozone is required, i. e., a very small quantity as compared with the requirements of known processes which have to be carried out with a considerable surplus of ozone. In the present process, however, it is essential 80 that all parts of the tobacco should come into intimate contact with the ozone. For this purpose the tobacco is not merely taken through the ozone current, but it is also subjected to a mixing process which consists in letting the material drop from the above-mentioned conveying band onto another band which also passes through the ozone current. From the second conveying band the tobacco falls on to a shaker composed of a plain or 90 perforated vibratory plate. The shaking is also carried out in the presence of ozone. In this manner the tobacco will not only be uniformly treated with the ozone, but it will also be intimately mixed. The treatment also 100 causes the essential oils in the tobacco to be uniformly distributed and mixed with the nicotine and the camphor, and brittleness of the tobacco due to empty cells will be avoided.

A mixture such as described is rich in 110 nicotine and therefore requires a slow movement of the conveying band and a comparatively speedy ozone current in order to keep the material in contact with the ozone for a long time. In the case of milder tobaccos 115 the speed of the band can be increased and that of the current can be reduced. Fine Levantine tobaccos such as Xanthi, Sam-soum, Seres and the like, which contain about 4.5 per cent nicotine only, require about 0.75 120 grammes ozone per 1000 kgs. tobacco.

The conveying device as well as the ozonizing elements are adapted for easy and exact regulation.

After the ozonizing, the raw tobacco is 125 given a rest for about 4 hours during which time it must not be touched with the hands or with iron implements. Contact with implements of wood or horn does no harm.

The better to open out the tobacco cells for 130

the reception of the ozone, the process may be carried out in the following manner, reference being had to the accompanying drawings:

5 After the tobacco leaves have been separated from one another as already explained and left to soak for 10 to 16 hours so as to contain at least 4 per cent moisture, they are, either cut or uncut, treated electrically with a view to break up the cells. For this purpose the moist tobacco is fed through a hopper *a* into a closed box *b* of wood or other suitable insulating material wherein it is spread thinly over an electrically charged conveying device such as an endless band *c*, a system of rollers or the like. The electricity may be supplied through spring contacts *e* to one of the carrier drums *d*, the opposite drum *d*¹ being connected through a conductor *f* to earth. Above the conveying band one or more ozone producers *g* are provided whence the ozone is fed on to the conveying band by nozzles *h* in opposite direction to the movement of the band. Thus 15 the ozone gas will be blown into the thin layer of electrically treated tobacco which is fed forwards by the band. Also in this case the ozone supply is regulated in accordance with the nicotine contents of the tobacco.

20 For the purpose of electric treatment, the conveying band, which is made of conducting material, for instance brass netting, is provided with pointed electrodes *k* in the form of studs, tines, hooks or brushes mounted on lists *l*. As an alternative, the band may be corrugated or formed with a rough or brush-like surface.

25 Under the conveying band *c* another band *n* is arranged so as to receive tobacco discharged through the meshes of the band *c*. Both bands deliver the tobacco into a hopper *o* which feeds it over a chute *p* into a collecting receptacle *q* wherein it is allowed to remain until ripe for further treatment.

30 The lists *l* may be insulated from one another as shown in Fig. 4 and adapted to contact with terminals at the ends of the band, in which case the current is led direct through the tobacco.

35 In the arrangement according to Fig. 5, lists *l* with pointed studs *k* are provided with contacts *s* which slide along commutator bars *r*. The sections *t* of the bars are spaced like the lists *l*, and alternate sections are connected to different poles of the electric supply. In this manner the direction of current passing through the tobacco will be continually changed.

40 The endless metal band may be replaced by a table or by a succession of plates fed through the box *b*.

45 Means are provided whereby the ozone supply and the conveying device may be independently controlled from outside the box.

50 The ozone producer *g* may be of any suit-

able known type. A conduit *u* is provided through which the ozone returns from the box *b* to the producer *g*. The only air vent of the box is through the hopper *a*. Otherwise the box is closed so as to enable the ozone supply to be regulated and so as to prevent the tobacco from being touched by hand during the operation.

55 The electric treatment may be effected by means of alternating current with a voltage of 110 or 220 V.

60 The conveying means may, as an alternative to the endless band, be composed of cylinders between which the tobacco is fed.

I claim:

1. A process of treating tobacco with ozone consisting in brushing the rib ends so as to clear them of foreign matter, moistening the rib ends with sterilized water, at room temperature, separating the tobacco leaves from one another, clearing away foreign plant matter, moistening the leaves in their entirety with sterilized water, leaving them in the moisture for 10 to 16 hours, treating the leaves with an electric current so as to break up the cells, passing the electrically treated leaves in a thin layer through and in opposite direction to an ozone current, and regulating the ozone supply in accordance with the nicotine contents on the treated tobacco.

65 2. A device for ozonizing tobacco comprising means for producing a blast of ozone, electrically conducting conveying elements adapted to take the tobacco in a thin layer through the ozone blast, and means for passing electric current through the tobacco layer.

70 3. A device as claimed in claim 2 wherein the conveying means consist of an endless travelling band.

75 4. A device as claimed in claim 2 wherein the conveying means consist of an endless travelling band, and tobacco-supporting elements on said band forming electrodes for the electric current.

80 5. A device as claimed in claim 2 wherein the conveying means consist of an endless travelling band, and metallic studs on said band adapted to support the tobacco thereon and to form electrodes for the electric current.

85 6. A device as claimed in claim 2 wherein the conveying means consist of an endless travelling band, electrically conducting lists on said band, pointed studs arranged on said lists so as to support the tobacco, and a commutator bar arranged so as to contact with said lists and form circuits through the tobacco layer.

90 7. A device for ozonizing tobacco, comprising an endless conveying apron made of metal netting, means for feeding the tobacco in a thin layer on to said apron, means for passing a current of ozone gas through the tobacco layer on the apron, means for passing electric current through the tobacco layer, a second
